CLAIM

The ornamental design for ring, as shown and described.

DESCRIPTION

FIG. 1 is a front perspective view of a ring showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear perspective view thereof.

The central gemstone shaded in grey has an appearance which contrasts with the gemstones that do not have grey shading.
